MULTIPLEX FUSE PLUG

Walter H. Wilson, Mansfield, Ohio

Application February 26, 1953, Serial No. 339,019

3 Claims. (Cl. 200—125)

1

This invention relates to a multiplex fuse plug and has for an object to provide an improved multiplex fuse plug having a multiplicity of separably blowable fuse portions of a single continuous fuse element and a corresponding multiplicity of intermediate off positions, thus providing a fuse which can be used for a plurality of circuit overloads, and which can be readily operated to an off position, irrespective of which fuse portion is in operation, without the necessity of removing the fuse to interrupt the circuit while working on the circuit line.

A further object of this invention is to provide an inexpensive multiplex fuse capable of several repeated uses, and wherein the blown fuse element containing cup may be easily replaced, thus making the fuse body available for subsequent series of uses.

A further object of this invention is to provide a multiplex fuse having a multiplicity of separate fuse element portions which are separably useable and blowable, each fuse element portion being in a separate chamber, and a hollow plug body into which the blown fuse may explode to use up its energy without affecting or blowing the fuse element portions in the remaining fuse element portion chambers.

A further object of this invention is to provide a multiplex fuse provided with an "off" position located adjacent each "on" position.

A further object of this invention is to provide a multiplex fuse body and cap both made of insulating material such as glass or suitable plastic within which the conductor elements may be permanently molded or secured, and provided with a readily replaceable continuous fuse element for providing a series of fuse element portions.

With the foregoing and other objects in view, this invention comprises the combination, construction and arrangement of parts hereinafter set forth, claimed and disclosed in the accompanying drawings, wherein:

Fig. 1 is a side elevational view of the multiplex fuse plug of this invention.

Fig. 2 is a top plan view of Fig. 1.

Fig. 3 is a partly sectional view on line 3—3 of Fig. 2.

Fig. 4 is a plan sectional view of the plug cap alone on line 4—4 of Fig. 3.

Fig. 5 is a plan view of the plug body, showing a fragmentary fuse element in its relative position.

Fig. 6 is a sectional view on line 6—6 of Fig. 5.

There is shown in said drawings the multiplex fuse plug 10 of this invention comprising a plug

2

body 11 and a rotatable plug cap 12 body of suitable insulating material, such as glass or other suitable insulating material capable of being molded to the desired shapes.

The plug body 11 has an open cupped end 14 having a floor 15 from which a counterbore extends providing a thimble shaped shell 16 which is completely hollow as at 17 except for the presence of a conductor 18 which connects to a contact head 19 at the bottom end thereof, and at its other end is molded through the floor 15 to extend within the inner wall 21 of the cupped end 14 and provide a first contact brush 22.

Also secured on the shell 16 is a contact ferrule 23, threaded in the usual manner, and having a conductor portion 24 extending therefrom and molded through floor 15 and terminating in a second contact brush 25 on the inner side of cupped end wall 21 and angularly spaced a suitable distance from the first contact brush 22. An indicia mark 26 is provided on the rim 27 of the cupped end 14 adjacent this second contact brush 25.

The rotatable plug cap 12 is likewise made of suitable and preferably transparent insulating material such as glass or plastic, and is cup shaped as at 30 and of a size to have its cup rim 31 nest within the cupped end 14 of plug body 11 and be supported on the plug body floor 15. The cap 12 is rotatably and removably held in the nested position by means of removable screws 32 threaded through the plug body cupped end wall 21 into a cooperating circumferential groove 33 in the cap 12. Obviously, removing the screws 32 permits the separation of the body 11 and cap 12. A handle 34 central of the cap 12 and exterior thereof provides for ready manipulation and rotation of the cap 12.

The cup 30 of the plug cap 12 is divided into a plurality of separate chambers 35 by radially extending webs 36 meeting at a center core 37 and terminating in the cup rim 31. The webs 36 are angularly spaced apart the same angular spacing as the two brush contacts 22 and 25.

Molded in and extended through the wall of cup 30 at 38, so as to extend in chord position across at least less than one of all the chamber 35, is a continuous fuse element 40 thus providing contact portions 41 external of the plug cap cup rim 31 and fuse element portions 42 in the chord position within the chambers 35.

As shown, the contact brushes 22 and 25, and thus also the chamber webs 36 and fuse contact portions 41, are sixty degrees apart, thereby providing five fuse element portions 42, each in a

separate chamber, and one chamber with no fuse element portion. The exterior top of the plug cap 12 is marked with angularly spaced indicia "1" to "5" inclusive and "0" on corresponding radial lines as at 43, and intermediate thereof, "off" indicia 44 is located, the indicia being so placed with relation of the fuse contact portions 41 that when the number indicia 43 is adjacent the marking indicia 26 on the plug body rim 27, a fuse element portion 42 is in operative circuit protective position, with two adjacent fuse element contact portions 41 in contact with the contact brushes 22 and 25, and when any one of the "off" indicia 44 is adjacent the marker indicia 26, the fuse element contact portions 41 are in the dotted line position 41' interrupting the circuit, as when it is desired to work on the circuit line.

In operation, when a circuit is overloaded, the fuse element portion 42 in the circuit position blows through the open side of its chamber 35 into the open hollow space 17 of shell 16 to thus expend its energy and thus refrain from overheating and blowing any other fuse element portion. When the cause of the overloaded circuit has been located and remedied, the circuit is restored by manipulating the handle 34 to partially rotate plug cap 12 and bring the next fuse element portion 42 into circuit position. If the circuit line is to be worked on at any time, the fuse need not be removed, but the cap is merely rotated to the adjacent "off" position.

When all the fuse element portions have been blown, the cap 12 may be removed by removing the screws 32 from the groove 33, and a new cap 35 with a new fuse strip therein may be substituted, or the entire plug may be replaced.

While the device has been shown and the structure described in detail, it is obvious that this invention is not to be considered as being limited to the exact form disclosed, and that changes in detail and construction may be made therein within the scope of what is claimed, without departing from the spirit of this invention.

Having thus set forth and disclosed the nature 45 of this invention, what is claimed is:

1. A multiplex fuse plug comprising a body of insulating material having an open cupped end having a floor from which a counterbore extends into the body providing a hollow thimble shaped shell, a contact head secured through the bottom of said shell, a conductor extending from said contact head and terminating within the inner side wall of said cupped end adjacent said floor providing a first contact brush, a contact ferrule on said shell having a conductor portion extending therefrom through said floor to within the inner side wall of said cupped end providing a second contact brush angularly spaced from said first contact brush, an open cup-shaped plug cap of insulating material nesting within said cupped end of said body adjacent said floor, means for removably and rotatably mounting said cap in nesting position in said plug cupped end, said plug cap having a plurality of angularly spaced radially extending webs dividing said open cup-shaped cap into separate chambers open on the side toward said hollow thimble shaped shell, a continuous fuse element secured through the cup wall of each separate chamber externally of each radial web and internally of at least one less than all of said separate chambers, said first and second contact brushes being angularly spaced the same spacing as said radial webs, manual rotating handle means on said plug cap exterior there-

5 of, multiplex fuse indicating indicia and intermediate "off" indicating indicia on said cap and a cooperating indicia on said plug body, whereby said plug cap may be rotated to position any two adjacent external portions of said fuse element in contact with said first and second brush contacts or to an "off" position between said contacts, the internal fuse element portion within the chamber between said contacted external portions blowing when overloaded into said hollow body shell without blowing the fuse portions in the other chambers.

2. A multiplex fuse plug comprising a body of insulating material having an open cupped end having a floor from which a counterbore extends into the body providing a hollow thimble shaped shell, a contact head secured through the bottom of said shell, a conductor extending from said contact head and terminating within the inner side wall of said cupped end adjacent said floor providing a first contact brush, a contact ferrule on said shell having a conductor portion extending therefrom through said floor to within the inner side wall of said cupped end providing a second contact brush angularly spaced from said first contact brush, an open cup-shaped plug cap of insulating material nesting within said cupped end of said body adjacent said floor, means for rotatably mounting said cap in nesting position comprising stud means, screws extending from the inner side of said cupped end into a cooperating circumferential groove in said plug cap, said plug cap having a plurality of angularly spaced radially extending webs dividing said open cup-shaped cap into separate chambers open on the side toward said hollow thimble shaped shell, each separate chamber having a continuous fuse element molded in and extending through its cup wall externally of each radial web and internally of at least one less than all of said separate chambers, said first and second contact brushes being angularly spaced the same spacing as said radial webs, manual rotating handle means on said plug cap exterior thereof, multiplex fuse indicating indicia and intermediate "off" indicating indicia on said cap and a cooperating indicia on said plug body, whereby said plug cap may be rotated to position any two adjacent external portions of said fuse element in contact with said first and second brush contacts or to an "off" position between said contacts, the internal fuse element portion within the chamber between said contacted external portions blowing when overloaded into said hollow body shell without blowing the fuse portions in the other chambers.

3. A multiplex fuse plug comprising a body of insulating material having an open cupped end having a floor from which a counterbore extends into the body providing a hollow thimble shaped shell, a contact head secured through the bottom of said shell, a conductor extending from said contact head and terminating within the inner side wall of said cupped end adjacent said floor providing a first contact brush, a contact ferrule on said shell having a conductor portion extending therefrom through said floor to within the inner side wall of said cupped end providing a second contact brush angularly spaced from said first contact brush, an open cup-shaped plug cap of insulating material nesting within said cupped end of said body adjacent said floor, means for removably and rotatably mounting said cap in nesting position comprising stud screws threaded through the side of said plug cupped end into a cooperating circumferential groove in said plug

cap, said plug cap having a plurality of angularly spaced radially extending webs dividing said open cup-shaped cap into separate chambers open on the side toward said hollow thimble shaped shell, each separate chamber having a continuous fuse element secured in and extending through its cup wall externally of each radial web and internally of at least one less than all of said separate chambers, said first and second contact brushes being angularly spaced the same spacing as said radial webs, manual rotating handle means on said plug cap exterior thereof, multiplex fuse indicating indicia and intermediate "off" indicating indicia

on said cap and a cooperating indicia on said plug body, whereby said plug cap may be rotated to position any two adjacent external portions of said fuse element in contact with said first and second brush contacts or to an "off" position between said contacts, the internal fuse element portion within the chamber between said contacted external portions blowing when overloaded into said hollow body shell without blowing the 10 fuse portions in the other chambers.
